UNITED STATES PATENT OFFICE.

ABRAHAM S. ADLER, OF BALTIMORE, MARYLAND.

LAST.

SPECIFICATION forming part of Letters Patent No. 379,039, dated March 6, 1888.

Application filed July 29, 1887. Serial No. 245,607. (No model.)

To all whom it may concern:

Be it known that I, ABRAHAM S. ADLER, a citizen of the United States, residing at the city of Baltimore and State of Maryland, have 5 invented certain new and useful Improvements in Lasts, of which the following is a full, clear, and exact description, reference being had to the accompanying drawings, forming a part of this specification, in which—

10 Figure 1 represents a side elevation of a last with my improvements attached. Fig. 2 is a top view of the last with the instep-block removed. Fig. 3 is the same view with the parts separated. Fig. 4 is a side elevation of the 15 central or foundation part detached.

My present invention has reference to means for fitting lasts; and it consists in the arrangement and combination of devices, hereinafter described and claimed.

20 To enable others skilled in the art to make and use my invention, I will describe the exact manner in which I carry the same out.

In the accompanying drawings, A, B, and C represent the three parts of a sectional last, 25 and D is the instep-block, fitting on the same. The part C, I call the "central" or "foundation" block, because upon this the last is built up, as will be hereinafter fully explained. This block is of uniform thickness from heel to toe, 30 and is provided with the dowel-pins d, for attaching to it the parts A and B, as shown in Fig. 3. On the block C, at the rear of the curve to receive the instep-block, I secure a spring-pawl, c, which, when thrown forward, 35 engages one of the graduated grooves d' in the end of the block D and holds the block D in any desired position, as shown in Fig. 1, the forward end of the block being held by the notch c', cut in the foundation-block C.

40 To the foundation-block C are fitted the right and left side pieces, A and B, to complete the last. These side pieces are of varying widths, but of same size or number in length to suit any foot, and the last can be 45 quickly changed from one width to another by

changing the side pieces, which are regularly proportioned, graded, and lettered.

Any one skilled in the art can readily change the last to fit any-formed foot and retain all the proper and required proportions throughout simply by changing one or both of the side pieces, which are regularly graded and lettered or numbered.

The instep is quickly regulated and determined by the pawl c being dropped into one 55 of the graduated grooves d' on the rear end of the instep-block, thus raising or lowering the instep, as may be desired.

With the mechanism I have thus described it is evident that after a last has been once 60 fitted to the foot a record can be made of parts used by letters or numbers, and the same exact fit can be reproduced at any time by reference to the record without again measuring the foot. On the foundation-blocks I find I 65 can form an increased number of different well-fitting lasts of the same size as foundation-block C by the use of properly-proportioned side pieces.

Having thus described my invention, what 70 I claim as new, and desire to secure by Letters Patent, is—

1. A last, substantially as herein described, consisting of the foundation-block C, provided with the pawl c, in combination with the side 75 pieces, A and B, and the instep-block D, provided with the graduated grooves d', all constructed as and for the purpose set forth.

2. The foundation-block C, provided with the pawl c and dowel-pins d, in combination 80 with the side pieces, A and B, perforated to receive the dowel-pins, and the instep-block D, provided with a graduated scale of grooves on its rear end, and constructed and arranged to operate substantially as and for the purpose 85 set forth.

ABRAHAM S. ADLER.
